UNITED STATES PATENT OFFICE.

PEDRO G. SALOM, JR., OF PHILADELPHIA, PENNSYLVANIA.

DESIGN FOR A TOY AUTOMOBILE.

Application filed February 6, 1925. Serial No. 12,287. Term of patent 7 years.

To all whom it may concern:

Be it known that I, PEDRO G. SALOM, Jr., a citizen of the United States, residing in Philadelphia, county of Philadelphia, and State of Pennsylvania, have invented a new, original, and ornamental Design for a Toy Automobile, of which the following is a specification, reference being had to the accompanying drawing, forming a part hereof.

In the drawing, Figs. 1 and 2 are respectively perspective views of a toy automobile embodying my new design.

I claim:

The ornamental design for a toy automobile substantially as shown.

PEDRO G. SALOM, JR.
